(57) **CLAIM**

The ornamental design for a wearable ring, as shown and described.

DESCRIPTION

FIG. 1 is a top, front perspective view of a wearable ring showing our new design;

FIG. 2 is a right side view thereof, wherein the left side is a mirror image of FIG. 2;

FIG. 3 is a top view thereof;

FIG. 4 is a front view thereof; and,

FIG. 5 is a rear view thereof.

The difference in shading in FIGS. 1-5 indicates a contrast of appearance of color only and does not depict any particular color, texture or material.
